(57) **CLAIM**

The ornamental design for a lighting fixture, as shown and described.

DESCRIPTION

FIG. 1 is a perspective view of a lighting fixture according to an example embodiment of the design;

FIG. 2 is a top view of a lighting fixture according to an example embodiment of the design;

FIG. 3 is a bottom view of a lighting fixture according to an example embodiment of the design;

FIG. 4 is a front view of a lighting fixture according to an example embodiment of the design;

FIG. 5 is a back view of a lighting fixture according to an example embodiment of the design;

FIG. 6 is a side view of a lighting fixture according to an example embodiment of the design;

FIG. 7 is another side view of a lighting fixture according to an example embodiment of the design;

FIG. 8 is a perspective view of a lighting fixture according to an example embodiment of the design;

FIG. 9 is a top view of a lighting fixture according to an example embodiment of the design;

FIG. 10 is a bottom view of a lighting fixture according to an example embodiment of the design;

FIG. 11 is a front view of a lighting fixture according to an example embodiment of the design;

FIG. 12 is a back view of a lighting fixture according to an example embodiment of the design;

FIG. 13 is a side view of a lighting fixture according to an example embodiment of the design;

FIG. 14 is another side view of a lighting fixture according to an example embodiment of the design;

FIG. 15 is a perspective view of a lighting fixture according to an example embodiment of the design;

FIG. 16 is a top view of a lighting fixture according to an example embodiment of the design;

FIG. 17 is a bottom view of a lighting fixture according to an example embodiment of the design;

FIG. 18 is a front view of a lighting fixture according to an example embodiment of the design;

FIG. 19 is a back view of a lighting fixture according to an example embodiment of the design;

FIG. 20 is a side view of a lighting fixture according to an example embodiment of the design;

FIG. 21 is another side view of a lighting fixture according to an example embodiment of the design;

FIG. 22 is a perspective view of a lighting fixture according to an example embodiment of the design;

FIG. 23 is a top view of a lighting fixture according to an example embodiment of the design;

(Continued)

FIG. 24 is a bottom view of a lighting fixture according to an example embodiment of the design;
 FIG. 25 is a front view of a lighting fixture according to an example embodiment of the design;
 FIG. 26 is a back view of a lighting fixture according to an example embodiment of the design;
 FIG. 27 is a side view of a lighting fixture according to an example embodiment of the design; and,
 FIG. 28 is another side view of a lighting fixture according to an example embodiment of the design.
 The broken lines showing in the drawings are included for the purpose of illustrating environmental structure and form no part of the claimed design.
